Int. Cl. D12—07

U.S. Cl. D71—1

*FIG. 2**FIG. 3*FIG. 1 is a top plan view of a helicopter showing my new design;

FIG. 2 is a side elevational view thereof taken from the bottom of FIG. 1; and

FIG. 3 is a front elevational view thereof taken from the right of FIG. 1.

The fragmented disclosure of a rotor blade in FIG. 1 is for clarity of illustration.

I claim:

The ornamental design for a helicopter, substantially as shown and described.
